BUILDING CONSTRUCTION

Robert Maxwell James, Buffalo, N. Y.

Application June 3, 1940, Serial No. 338,505

7 Claims. (Cl. 72—16)

This invention relates to a building construction and more particularly to a load supporting wall the erection of which provides finished surfaces on both sides, each of which can be of any desired appearance and suitable for either the exterior or the interior of the building.

One of the principal objects of the invention is to provide a wall construction, the load supporting members of which are studs which are faced with plates composed of one of the synthetic resin plastics preferably in combination with a substantial amount of filler to reduce cost, such plastics being available at low cost in a wide range of colors, finishes and physical characteristics and having the strength and weather resisting properties for use as both exterior and interior wall plates and being capable of being molded with a high degree of accuracy to provide ease in erection and to insure weather-tight joints between the panels.

Another object of the invention is to provide such a wall construction in which the studs forming the load carrying members can be made of wood or of concrete and in which, where Portland cement studs are used, the studs can be poured and built up progressively with the erection of the completed wall.

Another purpose is to provide plates for facing such a wall construction which are securely interlocked with one another and with the studs and in which the plates are so interlocked as to provide weather-tight joints.

Another object is to provide such plates which can be provided in a minimum number of shapes and at the same time not only provide the flat surface of the wall but also the exterior and interior corners of the outer wall of the house and its partitions.

Another aim is to provide such a construction which is adaptable to all building conditions and types of buildings including permitting the location of doors, windows or ornamentation as the architect may desire.

Another purpose of the invention is to provide such plates which can be erected in either break joint or stacked arrangement and in which the arrangement can be readily shifted from one to the other to suit the architectural effect desired.

Another object is to provide such plates which can be sawed in half to provide half sections, the plates being so constructed as to insure that such half sections interlock in the same manner as the whole plates to provide weather-tight joints.

Another object of the invention is to provide such a wall construction which has low thermal

conductivity; is fire resistant; possesses adequate strength both in its load supporting characteristics and also in the ability of the facing plates to withstand blows; and which can be rapidly erected by normally skilled workmen.

Another aim is to provide such a building construction in which substantially all of the facing plates can be removed from the studs without injury, thereby permitting the plates to be used over again after the building has been demolished.

Another aim is to provide such a building construction which is extremely inexpensive both in the cost of materials and in the labor of erection, thereby permitting the invention to be used in low cost housing.

In the accompanying drawings:
Fig. 1 is a fragmentary side elevation of a building constructed in accordance with my invention with studs of poured Portland cement.

Fig. 2 is a horizontal section taken on line 2—2, Fig. 1, and showing in dotted lines the manner in which a window and its casing can be installed and also showing the manner in which an interior partition can be joined to the outer wall of the building.

Fig. 3 is a fragmentary enlarged view similar to Fig. 2.

Fig. 4 is a fragmentary vertical section taken on line 4—4, Fig. 1, and illustrating the manner in which a lintel is provided over an opening, such as the window opening illustrated in Fig. 1.

Fig. 5 is a fragmentary vertical section taken on line 5—5, Fig. 1.

Fig. 6 is a fragmentary vertical section, on a reduced scale, taken on line 6—6, Fig. 5.

Fig. 7 is a perspective view, viewed from the rear side of one of the flat plates of synthetic plastic material illustrated in the previous figures and also showing the manner in which a clip can be interlocked with the base plates forming the inner and outer surfaces of the wall.

Fig. 8 is a perspective view similar to Fig. 7 viewed from the opposite or front side of the plate.

Fig. 9 is a perspective view similar to Fig. 7 of one of the curved exterior corner plates shown in Figs. 1—3.

Fig. 10 is a perspective view similar to Fig. 7 of one of the curved interior corner plates shown in Figs. 1—3.

Fig. 11 is a perspective view of one of the clips used to secure the plates to the studs.

Fig. 12 is a vertical fragmentary section similar to Fig. 5 and showing a modified form of the in-

vention in which wooden studs and sills are employed.

Fig. 13 is a perspective view of one of the base plate anchoring clips used with the wooden stud and sill construction illustrated in Fig. 12.

Fig. 14 is a fragmentary vertical section similar to Fig. 4 and showing a modified means for attaching the plates to poured concrete studs and including bent screws to secure a more reliable anchorage in the studs.

In its general organization the building construction embodying the present invention comprises a frame made up of a plurality of studs which can either be of poured concrete, as illustrated in Figs. 1-5, or of wood, as illustrated in Fig. 12, to which clips are secured, these clips being designed to interlock with keys formed in the rear faces of the face plates. The face plates are molded of a synthetic resin plastic and are formed to interlock with one another to provide weather-tight joints and also are provided with keys at predetermined places to provide flexibility in the application of the plates. The plates are made in the form of flat plates to cover the major flat surfaces of the wall; in the form of curved exterior corners to provide the exterior corners of the building; and in the form of curved interior corners to provide the interior corners of the building, the three forms being designed to interfit exactly in the completed structure.

As previously indicated, the wall made in accordance with the present invention is faced with relatively thin plates composed of a molded synthetic resin plastic which can contain a substantial amount of filler, such as wood flour, the plastic selected being determined by the color and appearance desired and by its ability to resist weathering, such plastics having the necessary strength and other qualities necessary for exterior and interior use in buildings. Except at the corners, these plates are in the form of rectangular panels indicated generally at 15 which, as best indicated in Figs. 1 and 8, have flat exterior faces 16. Along its upper edge each of these plates 15 is provided with a rearwardly offset, upwardly projecting tongue 17, the front face of which is substantially coplanar with the rear face 18 of the plate so as to provide a groove 19 for the reception of the lower edge of a plate in the next succeeding upper row. However, it is desirable that the front face of the tongue 17 be arranged a slight distance rearwardly of the rear face 18 of the plate so as to permit of the application of caulking or suitable weatherproofing material in the joints between the plates. This tongue extends from a distance short of one end 23 of the plate, as indicated at 20, to a point beyond the opposite end of the plate and at this opposite end is continued to provide a similar vertical tongue 21 which extends downwardly to a point 22 short of the lower edge of the plate.

The vertical edge 23 of the plate opposite the tongue 21 is formed to provide a groove 24 for receiving the tongue 21 of the next succeeding plate and for this purpose the plate is provided on its rear face adjacent this opposite vertical edge with a vertical rib 25, this rib being spaced from the edge 23 of the plate a distance slightly greater than the horizontal extent of the tongue 21 and being provided with a vertical flange or tongue 26 which together with the rear face 18 of the plate and the rib 25 forms the groove 24. This rib 25 and its tongue 26 extend the full height of the plate so that the groove 24 likewise

extends the full height of the plate to the base of the horizontal tongue 17. The rib 25 is also notched upwardly from its lower end along the flat rear face 18 of the plate, as indicated at 27, to permit the upper horizontal tongue 21 of one plate to be fitted against the rear face of another plate.

With a series of flat plates 15 provided with tongues and grooves as above described, it will be seen that these plates can be interfitted and interlocked to provide the flat surface for a wall as illustrated in Figs. 1, 2, 3, 4, 5, 12 and 14. Thus, in horizontal rows the tongue 21 of each plate 15 fits into the groove 24 of the next succeeding plate so that the outer and inner faces 16 and 18 of the several plates 15 are coplanar, as best illustrated in Fig. 2. In laying the next higher row of the plates 15, the lower edge of each of the plates is fitted into the groove 19 provided by the upper horizontal tongues 17 of the row of plates already in place, so as to provide a weather-tight horizontal joint between the several walls. Since in the molding of synthetic resin plastics the product can be held to extremely accurate dimensions, it will be seen that the tongues can be made to closely fit the vertical and horizontal grooves provided and insure weather-tightness in both the vertical and horizontal joints between the plates and also that these joints can be made extremely narrow.

Each plate 15 is additionally provided on its rear face 18 with vertical ribs 30, 31, 32 and 33 in addition to the rib 25. The rib 30 is arranged exactly one-quarter of the distance from the edge 23 of the plate to the opposite edge of the plate and is provided with a notch 34 similar to the notch 27 of the rib 25, this notch extending upwardly from its lower end against the rear face 18 of the plate. The rib 31 is arranged to one side of the vertical centerline of the plate and is provided with a notch 35 similar to the notches 27 and 34 of the ribs 25 and 30, respectively. In addition this central rib 31 is provided with a vertical flange or tongue 36 which is identical with the flange or tongue 26 of the rib 25 and provides a vertical groove 37, identical with the groove 24 provided by the rib 25 and its rib or flange 26. The purpose of providing the tongue 36 and groove 37 at the center of the plate is to permit of making half plates having an end groove similar to the whole plates by the simple expedient of cutting the whole plates in half. Thus it will be seen that by sawing the plate 15 along the line A—A in Fig. 7, which represents the vertical centerline of the plate, two half plates are produced, both of which half plates can be used at the ends of the rows of plates, as illustrated in Fig. 1. The two half sections from one plate will be slightly different from one another in that the half cut from the left of the whole plate 15, as viewed in Fig. 7, will not have a tongue 21 at one end. This is of slight practical consequence, however, as many of these can be used where the presence of a tongue is unnecessary, as at the window opening 65 or in interior work where the occasional absence of the tongue would be unimportant.

The rib 32 is arranged exactly three-quarters of the distance from the edge 23 of the plate to the opposite edge of the plate and is provided with a notch 38 at its lower end similar to the notches 27, 34 and 35 of the ribs 25, 30, 31, respectively. The rib 33 is arranged along the edge of the plate 15 opposite from the edge 23

and likewise is provided with a notch 39 which is similar to the notches 27, 34, 35 and 38 of the ribs 25, 30, 31 and 32, respectively. Each of the ribs 30-33 extends from the bottom edge of the plate the full height of the plate as with the rib 25.

For the purpose of attaching the plates to the studs, as hereinafter described, each of the ribs 25, 30, 31, 32 and 33 is shown as provided with an enlargement 40 at its upper end, each of these enlargements being of dovetail form in horizontal section and having its enlarged vertical rear end projecting rearwardly from the rear side of its supporting rib. The sides of the dovetail enlargements 40 are preferably vertical and the enlargements extend a substantial distance down the ribs although this distance is not critical.

The plates are secured to the studs by means of metal clips 45, each of which, as best shown in Fig. 11, comprises a flat metal back 46 from which integral vertical side wings 47 project forwardly to provide a dovetail groove 48 which conforms to the dovetail enlargements 40 of the ribs of the plates 15. The back 46 extends upwardly from the wings 47 and at its upper end is provided with a hole 49 to receive an attaching screw. The major axes of the wings 47 also preferably incline slightly toward each other from the bottom of the clip to the top so that in driving the clips down the dovetail projections 40, these wings are caused to firmly engage the sides of the dovetail projections 40 and frictionally grip these projections. The flat metal back 46 of each of the clips 45 is also formed above the wings 47 to provide an additional pair of wings 44 which are bent flat against the front face of the metal back 46 and form a stop to limit the downward movement of the clips 45 when so driven downwardly on the upper enlarged dovetail portions 40 of the plates 15.

In Figs. 1-5 is illustrated a building construction in which the studs are made of Portland cement which is poured as the erection of the wall with the plates 15 proceeds. In erecting a wall with poured concrete studs, indicated generally at 50, a foundation 51, as of poured concrete, is first provided, preferably with upstanding pins 52 at the places where the studs are to be arranged. These studs are designed to be placed on the standard 16" centers or any other center selected and for this purpose each of the plates 15 is of the same length as the selected center distance between the studs. Further, since the ribs 30 and 32 are arranged at exactly one-quarter and three-quarters of the distance, respectively, from the vertical edge 23 of each of the plates 15, it will be seen that the ribs 32 of each row of plates 15 will be arranged on exactly the selected centers and that also the ribs 30 of the series of plates will be arranged on the same centers. This will insure that the enlargements 40 at the upper ends of these ribs will be in proper position to be secured to the poured concrete studs by means of the clips 45.

Following the construction of the foundation 51 with the upstanding pins 52 a plurality of anchoring clips, indicated generally at 55, are laid on the foundation wall 51 preferably immediately adjacent each of the pins 52. These foundation clips 45 are made of sheet metal and each comprises a flat horizontal bottom portion 56, the central part 57 of which is preferably

offset horizontally to one side, as best illustrated in Fig. 7. At its opposite ends this body portion is provided with upstanding ears 58 which are of such form as to fit any of the notches 27, 34, 35, 38 or 39 provided at the lower ends of the ribs 25, 30, 31, 32 and 33, respectively.

A tube 60 made of paper, cardboard, metal or any other suitable material and of any suitable height, is then placed over each of the pins 52, 10 these tubes being held in a vertical position in any suitable manner and the lower ends of these tubes, of course, also covering the central part of each anchoring clip 55. The first row of plates 15 is thereupon set in position on the foundation 15 wall 51 against both sides of the paper tubes 60 so as to start both the exterior and interior wall surfaces. In so setting this first row of plates each of the ears 58 of the anchoring clip 55 is inserted in the notch at the lower end of that rib 20 of the plate 15 which coincides with the paper tube with which the clip is associated. It will therefore be seen that the anchoring clips 55 act as positive spacers so as to insure an exact spacing of the bottom of the inner and outer row of plates. 25 The purpose of providing the offset 57 in each of these anchoring plates is to insure that the clips can be located in proper position to catch the opposite ribs of the plates on opposite sides of the paper tubes 60 even though the pins 52 are not placed with a high degree of precision. Thus, 30 the clip can be arranged as shown in Fig. 7 or if, through slight inaccuracy, the pin 52 does not permit of such placing, the clip 55 can be turned end for end so that its offset portion 57 extends 35 in the opposite direction to avoid the pin.

The first row of plates 15 so anchored to the clips 55 are set up with the flange 21 of each plate being inserted into the groove 24 of the next succeeding plate. If the setting up of the plates 40 requires the use of the half plates, as illustrated in Fig. 1, one of the plates 15 is cut in two along the line A—A of Fig. 7 so as to expose the groove 37 for receiving the flange 21 of the next plate. At the time the first rows of plates 15 are being placed on opposite sides of the paper tubes 60, the clips 45, as best illustrated in Fig. 11, are slipped 45 over the dovetailed sides of the enlargements 40 of those ribs of the plates 15 which coincide with the paper tubes. These clips are placed so that their wings 47 50 embrace the dovetailed sides of the enlargements 40 by sliding the clips down from the top of the enlargements 40 so that these dovetail enlargements are caught in the dovetail grooves provided by the wings 47. The upper ends of these clips 55 thereby coincide with the paper tubes 60 and screws 61 are passed through the holes 49 of the clips and screwed into the adjacent walls of the paper tubes 60. For this purpose the entire shank of each of these screws is threaded so that the paper tube will be caught by the thread of the screw when it is finally drawn tight. It has been 60 found that a remarkably firm connection can be made by so screwing the clips 45 to the walls of the paper tube.

After the first inner and outer row of plates 15 have been so screwed in position, the second row of inner and outer plates 15 is set up in the same manner, this second row of inner and outer plates being arranged so that the tongues 17 along the upper edge of the base row fit against the rear faces 18 of the plates of the second row and into the notches 27, 34, 35, 38 and 39, respectively, of the ribs 25, 30, 31, 32 and 33 of the row being laid. As the row being laid is set up it similarly is provided with clips 45 for those dovetail enlarge- 70 75

ments 40 which coincide with the paper tubes 60 and these clips are screwed to the walls of the paper tubes. By providing both the one-quarter and three-quarter ribs 30 and 32 with dovetail enlargements 40, it will be seen that the plates 15 can be laid up either in the break joint relation shown in Fig. 1 or in a stacked arrangement, one of these ribs coinciding with a tube 60 where the tubes are arranged on the predetermined centers. The other ribs 25, 31 and 33 of the plates are provided with dovetail enlargements 40 for the sole purpose of permitting greater flexibility in the location of the studs and to permit employing intermediate studs between those on the predetermined centers where a concentrated load is to be supported by the wall, or for any other reason.

In the erection of the wall suitable temporary spacing boards or studs can be used to insure the exact spacing of the inner and outer plates, inasmuch as the paper tubes 60 are capable of being distorted and after a suitable number of rows of the exterior and interior plates have been screwed in position the paper tubes 60 are filled with concrete 68 so as to embed the last upper row of screws 61 which have been placed in position. After this concrete has set, the studs are in the form of concrete studs on predetermined centers and the screws 61 are embedded in these studs so as to securely hold the plates 15 to the studs.

To increase the strength of this securement, it has been found that bent screws, as indicated at 61a, can be screwed into the walls of the paper tubes 60 as easily as the straight screws shown in the other figures. It has also been found that where such bent screws 61a are employed they are much more firmly anchored in the concrete inasmuch as they cannot be pulled out of the concrete without distorting the screw or breaking away a part of the stud.

Where lintels are required over openings, such as the window opening 65 shown in Fig. 1, the lintel can be in the form of a sheet metal channel 66 having upright side flanges 67 which are spaced to embrace the paper tubes 60 and to engage the opposing faces of the ribs 25, 30, 31, 32 and 33 of the inner and outer plates 15, as best illustrated in Fig. 4. This lintel is supported on the through studs at opposite sides of the opening 65, the paper tubes 60 of these studs having been filled with concrete up to this point and since the upright flanges 67 of the lintel are spaced apart sufficiently to embrace the paper tube 60 it will be seen that any number of studs can be built up on this lintel as indicated by the central stud shown at the top of Fig. 1. After the plates 15 have been set up so as to leave the opening 65 as shown in Fig. 1, a window or a door frame can be set into this opening in the manner illustrated by dotted lines in Fig. 3, this provision of window or door cases forming no part of the present invention and hence not being illustrated or described in detail.

As illustrated in Figs. 12 and 13 the invention can also be carried out with a wooden stud and sill construction instead of the concrete stud and sill construction indicated in Figs. 1-5. As shown in Fig. 12 the frame of the building includes a wooden sill 70 which would usually be a standard 2" x 4" sill and which can be secured to the foundation wall 51 in any usual and well known manner. On the sill 70 wooden studs 71 can be set up on predetermined centers in the usual and well known manner. With the wooden construction the base row of plates would be secured by base clips of somewhat different form from the

base clips 45 used in connection with the poured concrete type of construction illustrated in Figs. 1-5. As best shown in Fig. 13, the clips 72 employed where wooden sills are used comprise an L-shaped strip of metal having a horizontal base, a short upstanding finger at one side which is adapted to fit into any of the notches at the base of any of the ribs provided on the back of the plate 15 and a long wing having a hole 73. Where wooden sills are employed, the clip 72 can be secured to the sill at intervals by means of screws or nails 74, the clips being arranged to enter one of the notches 27, 34, 35, 38 or 39 at the base of one of the reinforcing ribs on the back of the plate 15. It will be understood that as many of these clips can be provided as may be desired, usually such clips being provided at the opposite sides of the base of each stud to register with that rib of the plate 15 which coincides with the stud and an additional base clip also being preferably provided in position to hold the opposite end of each of the base plates. In other respects the plates 15 are laid up and secured to the wooden studs 71 in exactly the same manner as they are secured to the paper tubes 60 in the form of the invention shown in Figs. 1-5, except that the entire facing of outside plates can be laid up independently of the facing of inside plates if desired, it not being necessary, as with the poured concrete studs, that the erection of the outside and inside plates proceed simultaneously.

The corners of the building are completed by the use of exterior corner plates 75 illustrated in perspective in Fig. 9 and interior corner plates 76 illustrated in perspective in Fig. 10. These corner plates are shown as being rounded to provide rounding exterior and interior corners, but it will be understood that this is purely a matter of choice and that these plates could be square cornered if desired.

The exterior corner plates 75 are of the same general form as the flat plates 15 except that the exterior corner plates are longer and are provided with six vertical ribs instead of five. Of these ribs the first rib 77 is identical with the rib 25 on the flat plates, having a flange or tongue 26a forming an end groove 24a similar to the end groove 24 in each flat plate 15. The remaining ribs 78, 79, 80, 81 and 82 of the exterior corner plate 75 are each identical with the vertical ribs 30, 32 or 33 provided in the flat plate 15, each of these ribs, and also the rib 77 having a dovetail enlargement 40a at its upper end corresponding to the similar enlargements 40 on the upper ends of the ribs of the flat plate 15 and each of these ribs 77-82 also being notched at its lower end, as indicated at 83, in the same manner as with the vertical ribs on the flat plates 15. In other respects the form of each curved exterior plate 75 is identical with the flat plates, except for being curved and the same reference numerals have therefore been applied and distinguished by the suffix "a." The curvature of the exterior corner plate 75 is shown as confined to the space between the vertical ribs 78 and 79 so that these ribs project inwardly at right angles to each other and are capable of being secured by the clips 45 to the side of a corner stud 50, as best illustrated in Fig. 3. As shown in this figure and Fig. 2, these exterior corner plates 75 exactly join the flat plates 15 so that the two wall surfaces are joined by a smooth unbroken corner provided by these corner plates 75. It will be understood that where the exterior corner plates 75 are to be laid up in break

joint relation to one another, the plates 15 must be provided in rights and lefts, the rights differing from the lefts by having a reversed arrangement of the vertical groove 24a and the opposite tongue 21a.

The interior corner plates 16 must also be provided in rights and lefts and are used for all interior corners including the interior corners of a partition 90, as illustrated in Fig. 2. These interior corner plates 16 are of the same general form as the flat plates 15 except that the interior corner plates are shorter and are provided with four vertical ribs instead of five. Of these ribs, the first rib 91 is identical with the rib 25 on each of the flat plates 15, having a flange or tongue 26b forming an end groove 24b similar to the end groove 24 in each flat plate 15. The remaining ribs 92, 93 and 94 of each interior corner plate 16 are each identical with the vertical ribs 36, 32 or 33 provided in each of the flat plates 15, each of these ribs, and also the rib 94, having a dovetail enlargement 40b at its upper end corresponding to the similar enlargements 40 on the upper ends of the ribs of the flat plate 15 and each of these ribs 91-94 also being notched at its lower end, as indicated at 95, in the same manner as with the vertical ribs on the flat plates 15. In other respects, the form of each curved interior corner plate 16 is identical with the flat plates, except for being curved, and the same reference numerals have therefore been applied and distinguished by the suffix "b." The curvature of the inner corner plate 16 is at its extreme end and is shown in Fig. 10 as adjacent the rib 94, this rib thereby projecting at right angles to the other ribs, although in an opposite hand plate the curvature would be adjacent the rib 91 as with the inner corner best shown in Fig. 3. In securing an inner corner piece in position, the dovetail enlargement 40b of the rib 91 will generally be attached by means of one of the clips 45 to the adjacent stud, although this will, of course, depend upon the arrangement of the studs. The inner corner pieces 16 are not secured to the corner studs, this having been found not to be feasible.

From the foregoing it will be seen that the present invention provides a wall construction in which plates of an inexpensive plastic and of any suitable color or appearance are employed to provide the inside and outside of a stud wall by direct attachment to the studs. The use of plastics permits of producing the plates to exact dimensions and also provides a strong wall which will stand up under severe abuse and will also withstand weathering. It will also be seen that the wall can be erected rapidly by normally skilled workmen and is highly fire resistant even when wood studs are employed and since there is but slight contact between the plates and the concrete, where concrete studs are employed, and this further reduced by the presence of the paper shell around the studs, it will be seen that the wall has low thermal conductivity. The wall can also be rapidly erected and the construction is flexible enough to permit of incorporating any desired architectural effect. It will also be noted that the erected panels can readily be removed by breaking out the lowermost row of panels and sliding the remaining panels downwardly without breakage, this permitting the use of the invention economically in connection with temporary structures and also increasing the salvage value of a building made in accordance with the invention.

I claim as my invention:

1. In a building structure, a plurality of uniformly spaced studs, a plurality of rigid plates arranged in horizontal rows against said studs and each equal in length to the spacing of said studs and having their edges formed to interlock with one another, an integral vertical rib projecting rearwardly from the rear face of each of said plates one-quarter the distance from each end of each plate so as to permit said plates to be placed in centered breakjoint relation to one another with one of the said ribs of each plate in substantially centered abutting relation with a corresponding stud, and means fastening said ribs to said studs in said centered abutting relation therewith.
2. In a building construction, a supporting structure, a plurality of rectangular rigid plates laid against said supporting structure and each being provided along two meeting edges with a rearwardly offset tongue the front face of which is substantially coplanar with the rear face of the plate and each plate being provided on its rear face along the vertical edge of its other two meeting edges with a rib, a flange projecting outwardly from said rib parallel to said rear face and engaging the rear face of the offset vertical tongue of an adjacent plate, said rib projecting rearwardly from said rear face of said plate a distance greater than the rearward projection of said tongues and said rib being provided at its lower end with a notch engaging the rear face of the offset horizontal tongue of an adjacent plate, and means fastening the ribs of said plates to said supporting structure.
3. In a building structure, a plurality of uniformly spaced studs, a plurality of rectangular rigid plates laid against said studs and each equal in length to the spacing of said studs and each being provided along two meeting edges with a rearwardly offset tongue the front face of which is substantially coplanar with the rear face of the plate and each plate being provided on its rear face along the vertical edge of its other two meeting edges with a rib, a flange projecting outwardly from said rib parallel to said rear face and engaging the rear face of the offset vertical tongue of an adjacent plate, an additional vertical rib projecting rearwardly from the rear face of each of said plates one-quarter the distance from the same end of each plate whereby said additional ribs coincide with said studs and said additional rib projecting rearwardly from the rear face of each plate a distance greater than the rearward projection of said tongues and one of said vertical ribs being provided at its lower end with a notch engaging the rear face of the offset horizontal tongue of an adjacent plate, and means fastening said additional rib of each plate to a corresponding stud.
4. In a building structure, a plurality of studs each comprising a shell filled with poured concrete, a plurality of rigid plates each having vertical ribs projecting rearwardly from the rear faces thereof and means securing said ribs to said studs, comprising clips interlocking with said ribs and bent screws extending through said clips and shells and embedded in the concrete of said studs.
5. In a building structure, a plurality of studs each comprising a shell filled with poured concrete, a plurality of rectangular rigid plates laid up in horizontal rows against opposite sides of said studs, said plates having vertical ribs projecting rearwardly from the rear faces thereof

and provided with upwardly extending notches at their lower ends and provided with tongues along their upper edges fitting into the said notches of the next succeeding higher row of plates, means securing said ribs to said studs comprising clips interlocking with said ribs and fastening members extending through said clips and shells and embedded in the concrete of said studs and base clips spacing the base row of plates and each comprising a flat body portion and upstanding end ears engaging the said notches of opposite ribs of the inner and outer base rows of said plates.

6. A building unit of the character described, comprising a rectangular rigid plate adapted to be secured to a supporting structure and provided along one vertical edge with a rearwardly offset tongue the front face of which is substantially coplanar with the rear face of the plate and each plate being provided on its rear face along the opposite vertical edge with a rib and a flange projecting outwardly from said rib parallel to said rear face to engage the tongue of

an adjacent plate, and a second rib and flange substantially identical with said first rib and flange provided alongside the vertical centerline of each plate whereby a half plate having a marginal form corresponding to the whole plate is obtained by dividing a whole plate into halves.

- 5 7. In a building structure, a corner construction comprising a corner stud and studs adjacent said corner stud, an exterior L-shaped corner plate having a pair of vertical ribs on its inner face at its bend projecting at right angles to each other and an additional vertical rib spaced from said pair of ribs, means securing said first pair of vertical ribs to the sides of said corner stud, 10 15 means securing said additional vertical rib to one of said adjacent studs, an interior L-shaped corner plate on the opposite side of said studs and having a vertical rib spaced from its bend and means securing said last vertical rib to one of said 20 additional studs, said bend of said interior corner plate being spaced a substantial distance from said corner stud.

ROBERT MAXWELL JAMES.
